UNITED STATES PATENT OFFICE.

VINCENT BENDIX, OF CHICAGO, ILLINOIS.

STARTER FOR ENGINES.

1,146,992.

Specification of Letters Patent.

Patented July 20, 1915.

Application filed June 26, 1914. Serial No. 847,496.

To all whom it may concern:

Be it known that I, VINCENT BENDIX, a citizen of the United States, residing at Chicago, in the county of Cook and State of Illinois, have invented certain new and useful Improvements in Starters for Engines, of which the following is a specification.

My invention relates to a starter for an engine such as a gas engine and the object 10 thereof is to provide a simple, efficient and reliable device of this character operated by a prime mover of any kind, such for instance as an electric motor. My starter is of that 15 type having a screw shaft or the like operated by a prime mover either directly from the armature shaft or indirectly by gearing and having mounted thereon a driving member in the form of a pinion adapted to be automatically meshed in the rotation of the 20 screw shaft with some member of the engine and to be thereupon driven or rotated for rotating such engine member.

The particular object of this invention is to improve the structure of a construction 25 of this general type by the provision of the several advantageous features of construction and mode of operation which will be apparent from the description hereinafter given.

30 In the drawings, Figure 1 is a sectional elevation of direct driven type of starter embodying my invention; Fig. 2 a detail view of the driving connection between the motor and screw shaft but on a smaller scale; Fig. 3 a cross-section on the line 3—3 of Fig. 1; Fig. 4 an end view of the pinion with the weight removed; Fig. 5 a cross-section similar to Fig. 3 and illustrating the pinion co-operating therewith; Figs. 6 and 7 detail 35 views of the spring anchoring bolts and associated parts; Fig. 8 a view similar to Fig. 1 but illustrating the indirect drive; Fig. 9 a detail section illustrating the driving connection between the driving shaft and the screw shaft; Figs. 10 and 11 detail views 40 similar to Fig. 9 but illustrating modified forms of driving connection.

In the drawings, I have illustrated two different forms of drive from the prime 45 mover to the screw shaft, one being a direct drive as shown in Fig. 1 and the other an indirect drive as shown in Figs. 8 to 11. However, with this exception the general construction and the principle of operation 50 are the same in both instances.

Referring to the form of starter shown in

Figs. 1 and 2 the prime mover is here an electric motor 1 whose armature shaft is extended to form the driving shaft 2. This shaft is preferably tapered and is secured by 60 means of a key 3 to a collar 4, these parts being held together by means of a nut 5 screwing on the screw-threaded end of the armature shaft, Fig. 2. The collar when thus in place forms a component part of the 65 driving shaft.

The screw shaft has two separate screw-threaded portions, to wit, an intermediate portion 6, an outer end portion 7 and also an inner cylindrical portion 8 which is recessed to receive the smaller diameter of the 70 collar 4. The yielding driving connection is provided between the collar and the screw shaft, the same here comprising a spring 9 coiled around the cylindrical portion 8 of 75 the screw shaft with one end anchored to the collar and the other to such cylindrical portion by means of the two bolts 10 and 11 respectively. As shown the collar 4 and the cylinder portion 8 are in axial alinement 80 and capable both of a relative rotary movement for driving purposes and also a slight longitudinal movement for a purpose hereinafter explained. By preference the anchoring bolts have lock washers 12 provided 85 with lugs 13 on opposite sides, one of the lugs being adapted to be turned downwardly between the extreme end of the spring and the first coil and the other being turned upwardly against one of the flat sides of the 90 head of the nut, Figs. 6 and 7. In this manner the bolts are locked against accidental rotation or loosening.

The driving member of the device is here 95 shown as a pinion 14 screw-threaded upon the threads 6 and adapted to co-operate with the driven member of the engine to be started such as a wheel 15 like the fly wheel of a gas engine. By preference this pinion is weighted by means of the depending 100 weight 16 to insure the longitudinal movement of the pinion for automatic meshing purposes when the screw-shaft is rotated.

By preference the intermediate portion of the screw shaft has a plurality of separate 105 threads instead of one continuous thread. In the present instance there are three of such separate threads thereby providing a three-point bearing for the pinion at its inner and outer extremes of longitudinal 110 travel. The inner ends of the threads end rather abruptly in order to form shoulders

17 there being three of these shoulders and likewise the ends of the thread which co-operate with these shoulders are terminated abruptly to form opposing shoulders 18. 5 The cutting of the threads is such that when the pinion reaches its inward limit of travel all of the shoulders will contact simultaneously thereby providing a series of stops acting simultaneously and arranged equidistantly with respect to the circumference of the screw shaft. These stops prevent any possible binding of the pinion when it reaches its inward limit of travel. I do not, however, make any claim to this stop feature in the present application as I have made it the subject-matter of a separate application. With respect to the outer end of the screw thread 6 it is unnecessary to provide any stops inasmuch as the engine wheel 10 15 when started on its own power will dislodge the pinion in case there should be any binding thereof. However, the plurality (preferably triple) threads shown herein provide a three-point bearing of the pinion 20 25 against the thrust sleeve hereinafter described and centers it on the shaft.

Upon the outer screw-threaded portion 7 of the screw shaft is secured a sleeve 19 provided with an end flange forming a thrust collar having a bearing in a bushing 20 which is secured in the bearing 21 provided at the outer end of an inclosed casing 22 which in the present instance supports the electric motor. The threads on end 7 run 30 35 opposite to the main threads of the screw shaft with the result that when the shaft is rotated, the tendency is to lock the shaft and thrust collar together in automatic manner.

Describing the mode of operation and 40 starting with the pinion 14 in its inward or lefthand position on the screw shaft (Fig. 1) the electric motor has started whereupon the screw shaft is driven through the medium of the armature shaft 3, collar 4, and spring 9. Upon the rotation of the screw shaft 45 the pinion will be advanced to the right longitudinally of the screw shaft and intermesh with the engine wheel 15. When the pinion is in full mesh and its longitudinal movement has been arrested by the collar 19 it will be rotated by the screw shaft and consequently the wheel 15 will be rotated. When the engine begins to run on its own power and the wheel 15 is thereupon 50 55 rotated at an increased speed the pinion 14 will be automatically unmeshed by being moved to the left longitudinally of the screw shaft. After moving a slight distance away from the engine wheel after such unmeshing, the pinion will momentarily stop in its longitudinal movement and will rotate with the screw shaft. When the screw shaft has slowed down somewhat the pinion will thereupon move longitudinally back to its 60 65 normal or home position at which it is

stopped by the contact of the respective shoulders 17 and 18.

In the event that in the longitudinal advance movement of the pinion 14 its teeth should not register with the teeth of the engine wheel the screw shaft is capable of yielding slightly toward the left, the clearance space between the collar 4 and the cylinder portion 8 permitting of this endwise movement which is against the tension of the spring 9. Owing to this arresting of the pinion the latter will start to turn and thereupon the teeth will be brought into register and a complete and proper meshing assured. This yielding of the screw shaft 70 75 80 cushions the contact between the pinion and the engine member and prevents shock or jar of contact between said parts.

Referring to Figs. 8 and 9, there is shown the indirect drive for the screw shaft but the 85 construction is otherwise substantially the same and the corresponding parts will therefore be provided with the same reference numerals. According to this construction the armature shaft 2 carries a driving pinion 23 90 meshing with a gear 24 which is secured by keying to a short shaft 25. This shaft has its bearing at one end in the inclosed casing 26 and at its other end in the recess in the one end of the screw shaft. The spring 9 95 in the present instance is anchored at its inner end to a pin 27 secured to the gear 24 but at its other end is anchored to the bolt 11 as in the other instance.

In Fig. 10 I have shown a modified form 100 as compared with Fig. 9, according to which the short shaft 25 is made integral with the screw shaft thereby appearing as an extension 28 thereof on which the gear 24 is loosely mounted. In this instance the drive 105 is through the gear 24, pin 27, spring 9 and bolt 11 to the screw shaft. The extension portion 28 of the screw shaft has a telescoping fit in the driving member or gear 24 to permit of an endwise or longitudinal movement of the shaft.

In Fig. 11 I have shown still another modification according to which the shaft 25 has keyed to it the gear 24 and is provided with a collar 29 separate or integral 115 therewith. This collar corresponds with collar 4 of Figs. 1 and 2 and the spring 9 is anchored thereto and to the screw shaft by means of the bolts 10 and 11 respectively.

I claim:

1. A starter for engines comprising a shaft having a solid screw-threaded section, a driving device which is screw threaded upon the shaft and adapted to travel longitudinally thereon and to engage a part of 125 the engine to be driven, a driving member with which the shaft has a telescoping fit, and a yielding driving connection between said driving member and said shaft.

2. A starter for engines comprising a 130

shaft having a solid screw-threaded section, a driving device which is screw threaded upon the shaft and adapted to travel longitudinally thereon and to engage a part 5 of the engine to be driven, a driving member, the shaft having a longitudinal movement and having a sliding fit with respect to the driving member, and a spring driving connection between said driving member and said shaft.

3. A starter for engines comprising a shaft having a solid screw-threaded section, a driving device which is screw threaded upon the shaft and adapted to travel 15 longitudinally thereon and to engage a part of the engine to be driven, a driving member, the shaft having a longitudinal movement and having a sliding fit with respect to the driving member, and a spring secured 20 at one end to the shaft and coiled around an end thereof, the other end of the spring being secured to said driving member.

4. A starter for engines comprising a shaft having a solid screw-threaded section, 25 a driving device which is screw threaded upon the shaft and adapted to travel longitudinally thereon and to engage a part of the engine to be driven, a rotatable driving member with respect to which said shaft 30 has a bearing and with respect to which it has a longitudinal sliding movement, and a yielding driving connection between said driving member and said shaft.

5. A starter for engines comprising a shaft having a solid screw-threaded section, 35 a driving device which is screw threaded upon the shaft and adapted to travel longitudinally thereon and to engage a part of the engine to be driven, a driving member with which the shaft has a telescoping sliding fit, and a driving connection between 40 said driving member and said shaft.

6. A starter for engines comprising a screw-threaded shaft, a driving member 45 which is screw-threaded upon the shaft and adapted to travel longitudinally thereon and to engage a part of the engine to be driven, a driving shaft, one of said shafts being recessed at one end to receive an end of the 50 other shaft, and a yielding driving connection between the two shafts.

7. A starter for engines comprising a screw-threaded shaft having one of its ends recessed, a driving member which is screw-threaded upon the shaft and adapted to travel longitudinally thereon and to engage 55 a part of the engine to be driven, a driving shaft entering the recess of the screw shaft, and a yielding driving connection between 60 the two shafts.

8. A starter for engines comprising a screw-threaded shaft having one of its ends recessed, a driving member which is screw-threaded upon the shaft and adapted to 65 travel longitudinally thereon and to engage

a part of the engine to be driven, a collar secured to one end of the driving shaft and fitting into the recess of the screw shaft, and a yielding driving connection between the collar and screw shaft. 70

9. A starter for engines comprising a screw-threaded shaft having one of its ends recessed, a driving member which is screw-threaded upon the shaft and adapted to travel longitudinally thereon and to engage 75 a part of the engine to be driven, a collar secured to one end of the driving shaft and fitting into the recess of the screw shaft, and a yielding driving connection between the collar and screw shaft, consisting of a 80 spring coiled around said inner end of the screw shaft with one end anchored to the collar and the other end to the screw shaft.

10. A starter for engines comprising a screw-threaded shaft having one of its ends 85 recessed, a driving member which is screw-threaded upon the shaft and adapted to travel longitudinally thereon and to engage a part of the engine to be driven, a collar secured to one end of the driving shaft and 90 fitting into the recess of the screw shaft, and a yielding driving connection between the collar and screw shaft, consisting of a spring coiled around the inner end of the screw shaft, and bolts which are secured to 95 the collar and screw shaft respectively and to which the ends of the spring are anchored.

11. A starter for engines comprising a screw-threaded shaft, a driving member 100 screw-threaded thereon and adapted to travel longitudinally thereon and to engage a part of the engine to be driven, a driving shaft, a yielding driving connection between the two shafts consisting of a spring coiled 105 around one end of the screw shaft, rotatable fastening members connected respectively with the ends of the spring and with the two shafts for anchoring thereto the ends of the springs, and washers for said rotatable fastening members, each washer having two lugs, one of which engages between the end of the spring and the first coil and the other of which engages the fastening member itself to prevent rotation thereof. 110

12. A starter for engines comprising a screw-threaded shaft, a driving member which is screw-threaded upon the shaft and adapted to travel longitudinally thereon and to engage a part of the engine to be driven, a driving shaft, and a yielding driving connection between the driving shaft and screw-shaft, consisting of a spring coiled around the inner end of the screw shaft, 120 bolts which are secured to the collar and screw shaft respectively and to which the ends of the spring are anchored, and a washer for one of the bolts, such washer having two lugs, one of which engages between the end of the spring and the first 125

coil and the other of which engages the bolt itself to prevent rotation thereof.

13. A starter for engines comprising a screw threaded shaft, a driving member which is screw threaded thereupon and adapted to travel longitudinally thereon, a driving shaft, said two shafts being in alignment and telescoping at their adjacent ends and having longitudinal movement with respect to each other, and a driving connection between the two shafts.

14. A starter for engines comprising a screw threaded shaft, a driving member which is screw threaded thereupon and adapted to travel longitudinally thereon, a driving shaft, said two shafts being in alignment and telescoping at their adjacent ends and having longitudinal movement with respect to each other and a yielding driving connection between the two shafts.

15. A starter for engines comprising a screw threaded shaft, a driving member which is screw threaded thereupon and adapted to travel longitudinally thereon, a driving shaft, said two shafts being in alignment and telescoping at their adjacent ends and having longitudinal movement with respect to each other, and a spring connecting between the two shafts and constituting a yielding driving connection and also a resistance for said longitudinal movement.

16. A starter for engines comprising a screw shaft consisting of a screw threaded solid body portion and a recessed end portion, a driving member screw threaded upon the shaft and adapted to travel longitudinally thereon, a driving shaft telescoping into said end portion of the screw shaft, and a yielding driving connection between the driving shaft and the screw shaft.

17. A starter for engines comprising a screw shaft consisting of a screw threaded solid body portion and a recessed end portion, a driving member screw threaded upon the shaft and adapted to travel longitudinally thereon, a driving shaft telescoping into said end portion of the screw shaft, and the screw shaft having a longitudinal movement with respect to the driving shaft, and a spring forming a driving connection between the two shafts.

18. A starter for engines comprising a screw-threaded shaft having one of its ends recessed, a driving member which is screw threaded upon the shaft and adapted to travel longitudinally thereon and to engage a part of the engine to be driven, a driving shaft, a collar secured to one end of the driving shaft and fitting into the recess of the screw shaft, and a yielding driving connection between the collar and screw shaft, the screw shaft having a longitudinal movement with respect to the collar.

19. A starter for engines comprising a screw-threaded shaft having one of its ends

recessed, a driving member which is screw-threaded upon the shaft and adapted to travel longitudinally thereon and to engage a part of the engine to be driven, a driving shaft, a collar secured to one end of the driving shaft and fitting into the recess of the screw shaft, and a yielding driving connection between the collar and screw shaft, consisting of a spring coiled around the inner end of the screw shaft, the latter having a longitudinal movement with respect to the collar, which movement is resisted by the spring.

20. A starter for engines comprising an electric motor including its armature shaft, a screw-threaded shaft having its inner end recessed to receive such armature shaft, a yielding driving connection between the two shafts, and a driving member screw-threaded on the screw shaft and adapted to engage a part of the engine to be started.

21. A starter for engines comprising an electric motor including its armature shaft, a collar secured to its outer end, a screw-threaded shaft having its inner end recessed to receive such armature shaft, a yielding driving connection between the collar and screw shaft, and a driving member screw-threaded on the screw shaft and adapted to engage a part of the engine to be started.

22. A starter for engines comprising a rotatable shaft separately screw-threaded as to its outer end and its intermediate portions, a driving member screw-threaded upon said intermediate portion and adapted to engage a part of the engine to be started, a casing for said shaft and provided with a bearing, a sleeve screwing onto the screw threads on the outer end of the shaft and mounted in said bearing, and means for driving the shaft.

23. A starter for engines comprising a rotatable shaft reversely screw threaded as to its intermediate portion and outer end, a driving member screw-threaded upon said intermediate portion and adapted to engage a part of the engine to be started, a bearing, a sleeve screwing onto the end of the shaft and received by said bearing, and means for driving the shaft.

24. A starter for engines comprising a rotatable shaft reversely screw-threaded as to its intermediate portion and outer end, a driving member screw-threaded upon said intermediate portion and adapted to engage a part of the engine to be started, a bearing, a sleeve screwing onto the end of the shaft and received by said bearing, and means for driving the shaft, said sleeve being flanged at one end and forming a thrust collar.

25. A starter for engines comprising a rotatable shaft which is provided with a plurality of screw threads on the same portion of such shaft and terminating abruptly in the same transverse plane, a thrust collar at

the outer ends of such threads, and a driving-member screw-threaded upon said shaft and adapted to travel longitudinally thereon when the shaft is rotated and to contact the 5 ends of the threads and thereby be held centered when rotating with the shaft.

26. A starter for engines comprising a screw-threaded shaft, a driving member which is screw-threaded upon the shaft and

adapted to travel longitudinally thereon and 10 to engage a part of the engine to be driven, a driving shaft telescoping with the screw shaft, and a yielding driving connection between the two shafts.
